UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

STRAIN-RELIEF FOR PENDENT ELECTRICAL DEVICES.

1,254,703.

Specification of Letters Patent. Patented Jan. 29, 1918.

Application filed June 6, 1914. Serial No. 843,525.

To all whom it may concern:

Be it known that I, CHARLES J. KLEIN, a citizen of the United States, residing at Milwaukee, in the county of Milwaukee and 5 State of Wisconsin, have invented new and useful Improvements in Strain-Relief for Pendent Electrical Devices, of which the following is a full, clear, concise, and exact description, reference being had to the accompanying drawing, forming a part of 10 this specification.

This invention relates to strain relief means for pendent lamp sockets and similar devices.

15 One of the objects of the invention is to provide improved strain-relief means enabling the device to be conveniently and expeditiously wired.

20 A further object is to provide simple and efficient strain-relief means wherein the grip on the conductor is effected between the socket base and a loose member retained by a part of the casing.

25 Further objects and advantages will appear hereinafter in connection with the description of the embodiment of the invention shown in the accompanying drawing, wherein,

Figure 1 is a sectional view of a pendent 30 lamp socket.

Fig. 2 is a perspective view of the socket base and cap bushing, separated; and,

Fig. 3 is a plan view of the socket base.

The device, as illustrated in Fig. 1 comprises an insulating base 1 for supporting the current carrying parts of the socket, a metallic shell 2 inclosing said base, a metallic cap 3 releasably interlocking with the shell, and an insulating bushing 4 disposed 35 within the cap 3 and resting upon the base 1. The socket base 1 carries at its lower end a screw shell 5 for receiving a translating device and is provided with binding posts 6 on opposite sides for connection with line 40 wires entering the casing through the cap 3.

45 A suitable recess 7 is provided in the base 1 for housing a snap switch mechanism adapted to control the circuit of the translating device. In the embodiment shown 50 the socket is designed to receive a snap switch mechanism having a double-ended push button operating member, and openings 8 are accordingly provided through opposite walls of the base 1 to accommodate 55 the push buttons.

The socket base is also provided with grooves 9 leading vertically from the binding posts to the upper face of the base and thence extending in opposite directions adjacent the perimeter of the base through 90° 60 and meeting diametrically at the center of the base below the opening in the cap 3. In wiring the device, the conductors are brought into the casing through the bushing 4 in the conductor-receiving cap 3 and are 65 then manually positioned within the tortuous open grooves on the top of the base and brought down in the grooves 9 for connection to the opposite binding posts. The insulating bushing 4, which constitutes, in 70 effect, a cover for the base, or a filler for the cap section of the casing, is adapted to rest upon the upper surface of the base and retain the conductors in the grooves. The bushing is itself maintained in close 75 connection with the base by the cap 3 which interlocks with the shell.

It is to be noted that the binding posts 6 are accessible from the sides of the base and that the tortuous grooves of the latter 80 are entirely open so that the line wires may be readily bent to lie therein. Moreover, the insulating bushing 4 is the only member through which the line wires need be threaded and the same may rest within the 85 cap in any relative rotary position without affecting its capability of retaining the line wires in the grooves.

The interlocking means for the cap and shell may be any desired type. As shown, 90 the cap 3 is provided with two pairs of opposite inturned catches 10 which take into correspondingly located openings 11 in the shell. While the upper portion of the base 1 is provided with a circumferential 95 flange 12 which rests upon the upper margin of the shell, the catches 10 are free to pass through the grooves 9 in the sides of the base and thus engage with the openings in the shell. 100

What I claim as new and desire to secure by Letters Patent is:—

1. In a pendent electrical device, in combination, a casing having an opening for conductors, an insulating base therein having terminals for connection with such conductors and having tortuous grooves extending from adjacent said terminals to a point in alignment with the opening in said casing, said grooves having an acute angle at a 110

point out of alinement with the opening of said casing, and means interposed between said base and a section of said casing for retaining such conductors within a portion of 5 said grooves.

2. In a pendent electrical device, in combination, a casing having an opening for conductors, an insulating base therein having terminals for connection with such conductors and having tortuous grooves extending from adjacent said terminals to a point in alinement with the opening in said casing and disposed in a plane perpendicular to the axis of said casing, and an insulating annulus within said casing for retaining such conductors within a portion of said grooves. 10

3. In a pendent lamp socket, in combination, a metallic casing comprising a shell and a cap having an opening for conductors, an insulating base in said shell having exposed terminals on its sides for connection with such conductors and having open grooves extending from said terminals to the top of said base and thence tortuously to a point in alinement with said opening in said cap, and an insulating member within said cap having a flat face for retaining such conductors within the grooves in the top of said base. 15

4. In a pendent lamp socket, in combination, a metallic casing comprising a cap and a shell having an opening for conductors, an insulating base in said shell for the current-carrying parts having exposed terminals on its sides for connection with such conductors and having open grooves extending vertically from said terminals to the top of said base and thence circumferentially and radially to a point in alinement with said opening in said cap, and an insulating member 20 within said cap for retaining such conductors within the grooves in the top of said base and for insulating said cap from such conductors. 25

5. In a pendent lamp socket, in combination, a casing having a removable conductor-receiving section, an insulating base in said

casing having terminals for connection with such conductors and having tortuous open grooves extending from said terminals to a point in alinement with the opening in said conductor-receiving section of said casing, 50 said grooves having side walls presenting acute angles, and an insulating filler loosely disposed within said conductor-receiving portion and adapted to be clamped thereby upon the top of said base for retaining such conductors within the grooves in the latter. 55

6. In combination, a sectional lamp socket casing having a conductor opening, a base therein having terminals and having grooves of substantially uniform depth between said terminals and said opening, said grooves extending tortuously in one face of said base, and a loose cover for said grooves secured in place by assembly of the sections of said 60 casing. 65

7. In combination, a sectional casing having a conductor opening, a base having binding posts thereon for conductors entering through said casing opening and having open tortuous grooves therein disposed in a single plane to receive and inherently bind such conductors for strain relief of their binding post connections and means to confine the conductors within said grooves. 70 75

8. In combination, a sectional casing having a conductor opening, a base having binding posts thereon for conductors extending through said casing opening and having a centrally located recess communicating with 80 said conductor opening and tortuous grooves extending therefrom to receive and inherently bind such conductors for strain relief of their binding post connections, and means to confine the conductors within said grooves. 85

In witness whereof, I have hereunto subscribed my name in the presence of two witnesses.

CHARLES J. KLEIN.
